UNITED STATES PATENT OFFICE.

LOUIS COIN, OF TASSIN LA DEMI LUNE, NEAR LYONS, FRANCE.

FASTENER FOR SLIDING DOORS.

SPECIFICATION forming part of Letters Patent No. 727,293, dated May 5, 1903.

Application filed December 4, 1902. Serial No. 133,902. (No model.)

To all whom it may concern:

Be it known that I, LOUIS COIN, engineer, a citizen of the French Republic, residing at Tassin La Demi Lune, near Lyons, France, 5 have invented certain new and useful Improvements in Fasteners for Sliding Doors, of which the following is a specification.

This invention relates to a fastener for sliding doors; and the object of the invention is 10 to provide a simple article of this character adapted to effectively operate without the use of springs. Moreover, although this lock is composed of very roughly cast parts, yet the friction is reduced to a minimum for the 15 purpose of reducing the wear and tear to a minimum.

In order that my invention may be clearly understood, I will now proceed to describe it by referring to the annexed drawings, in 20 which—

Figure 1 shows the relative position of the parts when the door is closed. Fig. 2 shows the relative position of the parts during the opening of the door. Fig. 3 indicates the 25 positions which the parts occupy when the door is opened. Fig. 4 is a horizontal section.

My improved lock is composed of two principal parts: first, a latch *a*, the point *b* of which is conveniently curved to the proper 30 angle and can engage in a staple *c*, carried by the frame-post *d* of the door. This latch is mounted freely on a horizontal axle *e*, around which it is able to turn; second, a click-lever or catch *f*, hinging freely around 35 an axle *g*, parallel to the axle *e*. The movement of rotation of these two parts is limited by means of conveniently-arranged stops *h i k*. The axles *e g* and the stops *h i k* are fixed 40 permanently in a cavity or chamber provided in the movable door opposite the staple *c*. Fig. 4 shows how the axles and stop-pieces are preferably arranged.

I place two wooden cheeks *n* on one side and the other of the latch and click-lever. 45 These cheeks offer the requisite bearings or recesses to receive the axles *e g* and the stop-pieces *h i k*, whose length is such that they do not extend beyond the wooden cheeks *n*. The recess formed in the door *m* is closed on 50 each side by a metal plate *o*—for example, of brass—and on the front edge or jamb by an-

other plate *p* of the same kind. The plates *o p* are screwed onto the door *m*. This simple arrangement permits of easily placing in position and removing all the parts of the 55 lock, since none of them are screwed or otherwise fixed in the door *m*. It is only necessary to unscrew one of the plates *o* to be able to easily remove the whole of the lock.

The cheeks *n* and the plates *o* are pierced by a horizontal slot *q*, in which the spindle or axle *r*, carrying the handles or knobs, is capable of sliding movement or displacement. On this axle and between the two cheeks *n* is mounted a roller *s*. If the click-lever *f* were 60 not present, the latch *a* would rest permanently and by its own weight only on the roller *s*, so that by acting on one of the handles so as to give the spindle *r* a to-and-fro movement one would bring about the oscillation of the latch *a* around its axle *e*. The cheeks *n* are provided with another recess or gap *t*, and the plate *p* is pierced by a hole *u* in order to permit the passage of the staple *c* when the sliding door is completely closed. 75

The action of the lock will be easily understood. When the door is closed, the point *b* of the latch becomes engaged in the staple *c*, thus keeping the door closed. The click-lever *f* rests on the forward edge of the staple, 80 as represented by the dotted lines in Fig. 1.

In order to open the door, it is sufficient to actuate one of the knobs or handles in the desired direction. The spindle *r* is first of all displaced or slid along in the slot *q*, and this 85 brings about the elevation of the latch *a* by the roller *s*. As the pressure on the handle is continued the door *m* slides toward the right, which permits the click-lever *f* to come to rest on the stop-piece *h*. As soon as the 90 door is opened, one can act on the handle without inconvenience—that is to say, it need no longer be pressed to the right, the point of the latch therefore coming down on the point of the click-lever *f*. When it is desired to re-close the door, it is sufficient to push it against the door-frame *d*. The forward edge of the staple *c* thereupon raises the click-lever *f* and permits of the latch *a* resuming the position which it occupies in Fig. 1. 100

As will be seen, this lock depends only on the force of gravity. It does not carry any

spring, and its parts have only to overcome the insignificant forces due to their mere weight, whereby the friction and consequently the wear and tear are reduced.

5 Having thus described my invention and reserving to myself to carry out any modifications of detail likely to facilitate the carrying into practice, I claim as my exclusive and private property conformably with the
10 law—

1. A fastener for a sliding door comprising a casing, a pivoted gravity-latch in said casing, means for lifting the latch, a gravity click-lever shiftably supported independently of
15 said latch and adapted to hold the latch in its ineffective position when the door is open, means for maintaining the lever in its latch-holding position, and a keeper supported independently of the casing, coöperative with
20 the latch and adapted to project into said casing and to move the click-lever out of engagement with the latch, whereby the latter can

drop into its effective position to engage the keeper.

2. A fastener for a sliding door comprising 25 a casing, a pivoted gravity-latch in said casing, a sliding spindle carried by the casing for lifting said latch, a pivoted gravity click-lever adapted to hold the latch in its ineffective position when the door is open, means for 30 maintaining the lever in its latch-holding position, and a keeper supported independently of the casing, coöperative with the latch and adapted to project into said casing and to move the click-lever out of engagement with 35 the latch, whereby the latter can drop into its effective position to engage the keeper.

In testimony whereof I have hereunto set my hand in presence of two subscribing witnesses.

LOUIS COIN.
